Primary Examiner—Raphael Barkai*Attorney, Agent, or Firm*—Beveridge, DeGrandi, Weilacher & Young, LLP[57] **CLAIM**

The ornamental design of frame for sunglasses, as shown and described.

DESCRIPTION

FIG. 1 is a top plan view of a frame for sunglasses showing my new design;

FIG. 2 is a front elevational view thereof;

FIG. 3 is a bottom plan view thereof;

FIG. 4 is a rear elevational view thereof;

FIG. 5 is a right side elevational view thereof, the side opposite being a mirror image;

FIG. 6 is a sectional view taken in the direction of the arrows on line 6—6 of FIG. 2;

FIG. 7 is a partial sectional view taken on the line 7—7 of FIG. 2;

FIG. 8 is a partial sectional view taken on the line 8—8 of FIG. 2;

FIG. 9 is a sectional view taken on line 9—9 of FIG. 2; and,
FIG. 10 is a front perspective view of the design shown in FIGS. 1-5.

The broken line showing of the lens in FIGS. 2-7, 9 and 10 is for illustrative purposes only and forms no part of the claimed design.
